DESIGN FOR A BED JACKET

Edward Sitkin, New York, N. Y.

Application April 24, 1941, Serial No. 100,599

Term of patent 3½ years

To all whom it may concern:

Be it known that I, Edward Sitkin, a citizen of the United States and a resident of New York, in the county of New York and State of New York, have invented a new, original, and ornamental Design for a Bed Jacket, of which the following is a specification, reference being had to the accompanying drawing, forming part thereof, wherein:

Fig. 1 is a front view of a bed jacket showing my design, and

Fig. 2 is a rear perspective view of the bed jacket shown in Fig. 1.

I claim:

The ornamental design for a bed jacket, substantially as shown.

EDWARD SITKIN.
